CHENILLE TUFTING ATTACHMENT FOR
SEWING MACHINESPatrick H. Turley, Chattanooga, Tenn., assignor
of one-half to W. E. Dellinger, Rome, Ga.

Application August 20, 1938, Serial No. 226,004

1 Claim. (Cl. 112—79)

My invention relates to sewing machines, and more particularly to attachments for sewing machines for producing chenille tufts on fabric for use as bathmats, bedspreads and the like.

In the prior art, it has been the practice to pass a needle carrying a strand of yarn downwardly through the fabric, forming a loop below the lower side of the fabric. As the needle starts its upward travel, slack is developed in the loop, and as the needle is moved still further upwardly, a hook or finger, commonly called a looper, is passed through the loop to hold it, and prevent it from being pulled back up through the fabric, and finally the loop is severed by a cutter to form piles or tufts.

There are various combinations for accomplishing this result. However, there are certain features which are common to all. These features generally consist of a reciprocating needle for carrying the yarn through the fabric, a finger for movement across the plane of the path of movement of the needle and having a hook adjacent its forward extremity, and a cutting element pivotally or otherwise associated with the finger for cooperation with the finger to sever the loops.

Generally, this looper or finger either moves in an arcuate or swinging path with respect to the plane of the needle or at an angle with respect thereto. This, of course, results in uneven cutting of the loops. Such combinations are shown in Stewart 1,984,772, Warren 2,058,047, Boyce 1,963,349, and others.

The moving finger and cutting mechanism are ordinarily actuated by an oscillating shaft, Boyce, *supra*, or from the feed dog mechanism, Stewart, *supra*. In this way, the loops are never caught in the same position on the looper and are never clipped in the same way by the looper thus resulting in ragged tufts. In almost all of these constructions it will be noted that the blade is pivotally mounted upon the looper with a lower extremity pivotally mounted upon a frame or to a fixed part on the machine, so that if the blade is adjusted, at its lower end, then the looper must likewise be adjusted and if the looper is adjusted the blade must be adjusted, and when either of these elements are adjusted, the entire tufting machine is thrown out of balance.

Furthermore, if it is necessary to remove the finger or hook, then the whole attachment must be dismantled and the same is true if the blade is to be removed. When wear takes place on the looper, it is necessary to adjust all of the

parts to return the combination to operative condition. Further examples of such construction are shown in Boyce 1,880,192 and in Keeney, 1,855,916.

Another disadvantage is noted in connection with the Keeney patent and the patent to Boyce 1,963,349, in that the looper operates the blade and the cutting speed is, therefore, wholly dependent upon the speed of the looper, necessitating the use of sharp blades to obtain the proper cutting operation.

Applicant with a knowledge of all these defects in and objections to the prior art has for an object of his invention the provision of a tufting attachment employing independently actuated loopers and blades, so that the cutting speed is greatly increased by the separate movement of looper and blade, since the ability to cut is directly proportioned to the speed of the relative movement of the cutting parts.

Applicant has as another object of his invention the provision of a tufting attachment employing a looper for movement always in a direction transversely to that of the path of movement of the needle, catching each of the loops at substantially the same place giving them equal length and severing them at substantially the same point, providing piles which are even and similar.

Applicant has a further object of his invention the provision of a tufting attachment employing a transversely moving finger or looper driven from a central shaft of the sewing machine and an independently mounted and actuated blade for cooperation with the looper in severing the loops, thereby permitting the removal of the blade and looper independent of each other and eliminating the necessity for dismantling the whole attachment when one or both of these parts are removed.

Other objects and advantages of my invention will appear from the following specifications and accompanying drawing and the novel features thereof will be particularly pointed out in the annexed claim.

In the drawing, Figure 1 is a fragmental end view of my improved attachment mounted upon a sewing machine. Figure 2 is a fragmental side elevation of the same attachment mounted on a sewing machine. Figure 3 is a plan view of my improved attachment removed from the sewing machine. Figure 4 is an end elevation of the same attachment removed from the sewing machine. Referring to the drawing in detail, 55 I designates the head of the conventional sewing

machine having a needle bar 2 carrying a reciprocating needle 3 therein and held thereby by thumbscrew 4. Mounted beneath the bed plate of the machine and carried by ears projecting downwardly therefrom and mounted in appropriate bearings 6, 7 are the usual feed dog shafts. Mounted between the ears and beneath the bed plate is frame 12 having an elongated opening 17 through which screws are adapted to pass and seat in appropriate feet 34 of the bed plate. 15, 15 designate screws which seat in the frame and project into the elongated slots for adjusting the frame 12 with respect to the needle by engaging screws 8, 8. The nuts 16, 16 lock the adjusting screws 15 in position. The frame 12 has upwardly projecting ears which are recessed on their back sides to receive a slotted bar 20, which reciprocates freely in the recess.

Carried by the bar 20 is a block 32 which is secured thereto by screws 33. Mounted on the upper end of the block 32 and adjustable with respect thereto and easily removable therefrom is a looper finger or hook member 30 having a hooked end. The finger or hook member is secured to the upper end of the block by means of screws 31, and has elongated slots therein for adjustment with respect to the finger.

Pivotedly mounted upon the frame 12 at 27 is an arm 23, which projects upwardly adjacent the reciprocating finger 30. Adjustably carried by the arm 23 is a cutter blade 24 which is secured thereto by means of a screw 25 which passes through an elongated slot in the arm 23 to permit adjustment of said blade with respect to the finger.

When mounted on the machine, as shown in Figure 1, the pivoted arm 23 is joined to the feed dog operating lever 5 by means of a link 21 which is pivoted at one end to the arm 23 by means of screw 22 and at the other end carries a finger 18 which seats in an opening in the feed dog carrying rod 5, thereby permitting pivotal movement.

Mounted on the rear face of the bar 20 is a channel shaped member 13 having a block 14 seated in a recess therein. The channel member 13 is joined to the rear face of the bar 20 by means of screws 34. Projecting longitudinally of the bed plate, beneath it and intermediate the two feed dog shafts is a central oscillating

shaft 11 driven from the main needle bar shaft in the conventional manner. Mounted on the end of this oscillating shaft 11 is a collar 10 carrying an offset pin 9 which sits in block 14.

5 In its operation, the needle bar 2 reciprocates up and down in the head 1. As it passes downwardly through the fabric, carried on the upper surface of the bed plate, the strand of yarn accompanies it and as the needle reaches its lower extremity and begins its upper movement, slack is developed in the loop or strand of yarn passed down through the fabric. At this point, the oscillating shaft is in movement causing pin 9 to impart a reciprocating motion to bar 20, 10 thereby moving the looper in the direction of the needle and passing the hook 30 between the needle and the strand of yarn thereby catching the loop. As the needle moves further upwardly and passes out of the fabric, the loop of yarn is drawn tighter about the looper or finger 30 and the finger 30 moves back to its initial position. This operation is repeated over and over again and loops are passed one after another upon the finger 30. 15 As the looper 30 moves back to its initial position with more than one loop thereon, the cutter blade is actuated by the movement of the feed dog bar 5, so that it clips the loop by its cooperation with the cutting edge on the looper and acts as a scissors. The relative movement of both the looper and the blade creates a large cutting speed and insures that the loop is cut, even tho the blade may be dull since the cutting is proportioned to the cutting speed between the two cutting members.

20 25 Having thus described my invention, I claim:
A combination of the character described comprising a reciprocating needle for passing a strand of yarn down through a fabric to form loops, a frame positioned beneath the fabric and having a longitudinal groove formed in a face thereof, a looper slidably mounted in said groove for movement substantially transversely to the plane of reciprocation of the needle for engaging and holding the loops, a pivoted cutter independently mounted from the looper upon the frame for cooperation with said looper to sever the loops, and means independent of said looper for actuating said cutter.

PATRICK H. TURLEY.
